UNITED STATES PATENT OFFICE

HOWARD C. BORTEL, OF TOLEDO, OHIO, ASSIGNOR, BY MESNE ASSIGNMENTS, TO THE DURA COMPANY, OF TOLEDO, OHIO, A CORPORATION OF OHIO

WINDOW REGULATOR

Application filed November 23, 1925. Serial No. 70,853.

The invention relates to window regulators and has for its main object the provision of arms for engaging the closure or window at spaced points and exerting substantially equal effort upon the closure to operate the same. Another object is to provide a unit window regulator in which the one mounting plate carries all of the elements. A further object is the provision of independent counterbalancing springs for the lifter arms. With these as well as other objects in view the invention resides in the novel features of construction and combinations and arrangements of parts as more fully herein-
15 after set forth.

In the drawings:—

Figure 1 is an interior side elevation, partly broken away, of a motor vehicle door having applied thereto a window regulator embody-
20 ing my invention;

Figures 2 and 3 are respectively cross sections on the lines 2—2 and 3—3 of Figure 1;

Figure 4 is a rear view of a portion of the regulator.

As shown in the present instance, my invention is applied to the door 1 of a motor vehicle having the opening 2 in its upper portion and the chamber 3 in its lower portion
30 for receiving the closure or window 4 when lowered from a position closing the opening.

5 is the mounting plate of the window regulator located below the opening 2 and provided at its lower corners with the laterally offset portions 6, which are in the present instance outwardly offset. 7 are lifter arms suitably connected at their outer ends to the closure 4 and pivotally mounted near their inner ends upon the mounting plate 5. These
40 arms extend parallel to the mounting plate and lie adjacent to the outer surfaces of its offset portions and are connected thereto by means of the pivots 8. 9 are convolute counterbalancing springs located at the inner
45 sides of the offset portions and in the recesses formed thereby, one end of each of these springs being connected to its pivot 8 and the outer end being hooked around the transverse inwardly extending ear 10 at the lower
50 end of the mounting plate and near its corner.

For actuating the lifter arms 7 so that they will exert substantially equal effort upon the closure 4 I have provided the equalizer or evener 11 which is located between the offset corner portions 6 of the mounting plate 5 and is pivotally connected at its ends to the links 12, which in turn are pivotally connected to the inner ends of the lifter arms. The evener is pivotally connected at its middle to the nut 13 which threadedly engages the vertical screw 14, this screw being journaled at its lower end upon the transverse inwardly extending ear 15 of the mounting plate 5 and being journaled at its upper end in the gear housing 16, which is secured to the outer side of the mounting plate. 17 is the operating handle and 18 is suitable gearing within the gear housing 16 for rotating the screw 14 from the handle.

From the above description it will be readily seen that I have provided a simple compact construction of window regulator which is built up in tandem fashion and is particularly adapted for use with heavy closures or windows such as used in busses.

What I claim as my invention is:

1. In a window regulator, the combination with a closure, of a plurality of pivotal arms for operating said closure and actuating means for said arms including a pivotal equalizer and connections between said equalizer and arms.

2. In a window regulator, the combination with a closure, of a plurality of pivotal arms for operating said closure, a member reciprocable in the direction of travel of said closure, and means connected to said reciprocable member and to each of said arms for equalizing the effort exerted upon said closure by said arms.

3. In a window regulator, the combination with a vertically movable closure, of a plurality of pivotal arms engaging said closure at spaced points, and actuating means for said arms including a vertically extending screw, a nut engaging said screw, an equalizer pivotally connected to said nut and links pivotally connected to said equalizer and arms.

4. In a window regulator, the combination

with a closure, of a mounting plate having a laterally offset portion, an arm for operating said closure, said arm being located at the outer side of said offset portion, a pivot ⁵ for said arm extending through said offset portion and a convolute spring located at the inner side of said offset portion and in the recess formed thereby, said convolute spring being connected to said arm to effect ¹⁰ a counterbalancing effect thereupon.

5. In a window regulator, the combination with a closure, of a plurality of arms for operating said closure, and actuating mechanism for said arms, including means for ¹⁵ equalizing the effort exerted upon said closure by said arms.

6. In a window regulator, the combination with a closure, of a plurality of arms connected to said closure at spaced points ²⁰ for operating the same, and actuating mechanism for said arms, including means for equalizing the effort exerted upon said closure by said arms.

7. In a window regulator, the combination ²⁵ with a closure, of a plurality of pivotal arms having one end operatively engaged with said closure, a pivotal equalizer connected to the opposite ends of said arms, and means associated with said equalizer for actuating ³⁰ said arms.

In testimony whereof I affix my signature.
HOWARD C. BORTEL.
